INTERNAL TEMPERING NOZZLE

Charles E. Mongan, Jr., Hartford, Conn., assignor
to Hartford-Empire Company, Hartford, Conn.,
a corporation of Delaware

Application November 25, 1939, Serial No. 306,103

8 Claims. (Cl. 49—45)

The present invention relates to tempering hollow glassware, such as bottles and jars, each of which has a single restricted opening.

It provides a novel internal cooling nozzle adapted to enter the ware through the restricted opening and to apply a cooling medium as, for example, air or steam, to the internal walls by a plurality of jets, and to remove the spent medium through a plurality of spaced exhaust openings. The nozzle is so constructed and arranged as to provide a large number of closely spaced jets of cooling medium originating from holes, distributed substantially completely over the portion of the nozzle surface below the entrance to the neck of the ware. These holes are of such number and size and so directed toward the walls of the ware as to bathe the entire surface of the walls with chilling medium without necessarily causing relative rotation or other movement between the ware and the nozzle. If desired, however, the nozzle and the ware may be moved relatively to each other either about or along the axis of the nozzle, or both, and the movement may be either rotary, oscillatory and/or reciprocatory.

A principal object of the invention, therefore, is to provide such a nozzle which will completely bathe the inner walls of the article with chilling medium in accordance with a pattern which is selected or predetermined in accordance with the characteristics of the bottle.

A more specific object of the invention is to provide a new and useful construction of nozzle by which the above stated objects may be readily accomplished.

The nozzle may be employed as part of any suitable apparatus as, for example, that disclosed in the application of Thomas D. Green, Serial No. 306,085, filed November 25, 1939, by which the glassware, while being cooled, may be held by tongs and locked in proper alignment by a member contacting the rim of the ware, and by which, when desired, the rotary and/or reciprocatory movement of the nozzle and ware, one relative to the other, may be effected.

The above recited and other features of my invention will be apparent from the following specification directed to a practical embodiment of the invention as shown in the drawing, in which:

Figure 1 is a view, principally in vertical section, of one form of nozzle of my invention shown in association with a narrow neck bottle held by tongs and a locking member, a portion of the nozzle being shown in elevation.

Fig. 2 is an enlarged section on line 2—2 of Fig. 1, and

Fig. 3 is a view in elevation of a combined tong and nozzle supporting and operating mechanism with which the nozzle of Figs. 1 and 2 may be employed, the view also showing an associate device for cooling the bottle externally.

The apparatus of Fig. 3 is substantially the same as that shown in the aforesaid Green application and as shown, comprises a tubular carrier 11 mounted in a bracket 12. Within the carrier 11 and extending above and below it is a tubular member 13 which carries a sleeve 14 providing a mounting for tongs 15. A locking member 16 is mounted on the lower end of the tubular member 13. The member 13 and tongs 15 are mounted for rotation, when desired, through a beveled gear 18 and through connections shown by a motor 19. If desired, the gear 18, and hence the member 13 and tongs 15, may be given an oscillatory movement by the substitution of means, not shown, for the driving means illustrated.

The nozzle 20 is removably carried by a pair 25 of concentric tubular members 21 spaced apart but secured together within the member 13, above which they extend, to carry the beveled gear 22 by which the nozzle may be rotated or oscillated about its axis, the means shown being adapted for rotation of the gear 22. It is to be understood that these means may, if desired, be altered to effect oscillation of the gear.

The nozzle may be moved vertically relative 35 to the article of glassware gripped by the tongs by means including the lever 23 and link 24, connected to sleeve 25 of the member 21 between the collars 26 and 27. This reciprocation may be periodic and in accordance with 40 any desired pattern and may be caused by a cam (not shown) operating on the lever 23. The external cooling device indicated at 28 may be rotated through sprocket 29.

The locking member 16 may, if desired, be 45 provided with serrations 30 to provide exits of selected size for a predetermined portion of the spent cooling medium which passes through the restricted opening 31 between the nozzle and the walls of the finish, to scrub the internal walls of the neck of the bottle. Such an arrangement may provide adequate, without excessive, chilling of the neck of the ware.

The nozzle 20 is provided with an outer tubular shell 32 and an inner casting 33 providing an 50 internal bore 34 and longitudinally extending

radial ribs 35, through which are a plurality of passages 36 communicating with jet holes 37 in the shell for the introduction into the bottle of cooling medium from the bore 34. The spaces between adjacent ribs 35 and the shell 32 provide a plurality of longitudinally extending exhaust passages 38 which communicate with the interior of the ware through exhaust ports 39.

The cooling medium is supplied through the pipe 43 and passages (not shown) to the bore 34, and the exhaust is through other passages (not shown) from passages 38 to exhaust pipe 44 (Fig. 3).

The lower end of the bore 34 may be closed by a removable tip 40 which is provided with a plurality of closely spaced jet holes 41 through which jets may be directed upon the bottom and lower corners of the ware. The passages 38 are open at the bottom of the nozzle and provide exhaust ports 42 adjacent to the bottom of the bottle.

In Fig. 2 the ribs are shown as being 12 in number, but obviously this number may be increased or diminished as may be desired. When the nozzle and ware are to be maintained relatively stationary, the greatest number of such ribs as may be conveniently provided is desirable to provide as great a number of jet openings as possible. As shown in Fig. 1, the jet holes 37 are arranged in closely spaced relation circumferentially of the nozzle and in closely spaced relation in vertical rows throughout all portions of the periphery of the shell from the lower end thereof to a point just short of the neck of the bottle. The exhaust ports are similarly arranged in closely spaced circumferential and vertical rows, the rows of exhaust ports alternating with those of the jet holes.

It is to be understood, however, that the exhaust ports may be otherwise arranged so long as they provide sufficiently localized and adequate exhaust ports to remove the spent gases without undue interference with the intended operation of the cooling jets. If desired, as in cases where relative cross sections of the opening into the bottle and of the lower portions of the cavity thereof create such divergence of the cooling jets as to create any tendency toward spotty or local cooling, the nozzle may be rotated or oscillated and/or reciprocated to cause the jets to scan the inner surface of the bottle, and thus avoid such spotty chilling.

Obviously the inlets or the exhaust openings may take the form of elongate openings or slots and these may overlap so long as they provide jets in suitable number and kind to effect the complete bathing of the surface that is to be cooled directly by the jets and to supply the chilling medium in accordance with the pattern required for the particular article of glassware being tempered.

The cooling medium may be applied to the internal nozzle prior to or simultaneously with the application of an external chilling medium through the cooler 28 or any other suitable means. In some cases the tempering may be carried on without the use of an external cooler, the chilling of the exterior of the bottle being effected by radiation to normal or even to heated surroundings.

Various modifications of my invention may be made without departing from the invention as expressed in the accompanying claims.

Having described my invention, what I claim is:

1. A tempering nozzle adapted to chill the internal surface of an article of glassware having a neck and a restricted opening therethrough, comprising an elongate body adapted to extend into the article through said restricted opening, said body being provided internally with a longitudinally extending central chilling fluid medium intake passage and with a plurality of longitudinally extending fluid medium exhaust passages in parallel spaced relation around the intake passage, said elongate body also being provided with closely spaced jet openings and exhaust ports opening through the outer periphery thereof and distributed over substantially the entire surface of the portion of the elongate body that is adapted to extend into the article beyond the neck thereof and with laterally extending passages connecting said jet openings with said longitudinally extending intake passage, said exhaust ports communicating with said exhaust passages, a perforated tip at the outer extremity of the elongate body provided with closely spaced jet openings in communication with said intake passage, said elongate body having a plurality of further exhaust openings surrounding said tip at the outer end of the body and in communication with said exhaust passages in said body.

2. A tempering nozzle according to claim 1 in combination with means for effecting relative movement between the nozzle and the article of glassware while the body of said nozzle extends through the restricted opening in the neck of the article into the interior thereof.

3. A tempering nozzle according to claim 1 in combination with means for effecting relative rotary movement between the nozzle and the article of glassware about the axis of the nozzle while the body of the nozzle extends into the interior of said article.

4. A tempering nozzle according to claim 1 in combination with means for effecting relative movement between the nozzle and the article of glassware along the axis of the nozzle while the body of said nozzle extends into the article of glassware.

5. A tempering nozzle for internally chilling an article of hollow glassware having a single restricted opening, comprising an outer tubular shell, an inner tubular member within the outer shell in spaced relation therewith, the bore of said inner tubular member providing a passage for conducting cooling fluid longitudinally of the nozzle, a plurality of longitudinal ribs extending radially outward from the inner tubular member to the outer shell, said nozzle having a plurality of cooling fluid discharge passages extending radially from said bore through the inner tubular member, the ribs and the outer shell, said ribs being spaced apart to provide longitudinally extending exhaust passages in the nozzle, said outer shell being provided with exhaust ports extending from said exhaust passages through the walls of said outer shell.

6. A tempering nozzle according to claim 5 and comprising also a removable tip at the outer end of the inner tubular member, said tip having perforations for the discharge of jets of cooling fluid from the bore of said inner tubular member at the outer end of the nozzle, the exhaust passages of said nozzle being open at their outer ends adjacent to said tip for the exhaust of spent cooling fluid.

7. A tempering nozzle for chilling the internal surface of an article of hollow glassware having

a single restricted opening, comprising an outer tubular shell, an inner tubular member within the shell having a bore for conducting cooling fluid longitudinally of the nozzle, a plurality of longitudinal ribs extending radially outward from the inner tubular member to the outer shell, said nozzle having a plurality of passages extending through the ribs and shell and communicating at their inner ends with the bore to direct jets of cooling fluid outwardly from the nozzle, said nozzle also having longitudinal passages between adjacent ribs and exhaust ports in the outer shell in communication with said longitudinal passages for exhausting spent cooling fluid, and a closure for the end of the inner tubular member having holes therein for discharging jets of cooling fluid from the end of the nozzle.

8. In apparatus for tempering glass bottles or

other glass containers, a nozzle comprising an elongate body insertable into the container to be tempered and provided with cooling medium discharge orifices at closely spaced points distributed throughout its entire surface area and with exhaust ports for the spent medium also distributed throughout said entire surface area and respectively located at points spaced closely with respect to one another and to the discharge orifices, said body having a longitudinally extending central cooling fluid supply passage and laterally extending passages connecting said central passage with said discharge orifices and having a plurality of longitudinally extending spent cooling medium exhaust passages in parallel angularly spaced relation around the central supply passage and communicating with the exhaust ports.
